(57) **CLAIM**

The ornamental design for a multi-chamber pellet die apparatus, as shown and described.

DESCRIPTION

FIG. 1 is a top perspective view of the multi-chamber pellet die apparatus;

FIG. 2 is a front view of the multi-chamber pellet die apparatus;

FIG. 3 is a back (rear) view of the multi-chamber pellet die apparatus;

FIG. 4 is a left view of the multi-chamber pellet die apparatus;

FIG. 5 is a right view of the multi-chamber pellet die apparatus;

FIG. 6 is a top view of the multi-chamber pellet die apparatus;

FIG. 7 is a bottom view of the multi-chamber pellet die apparatus;

FIG. 8 is an exploded top perspective view of the multi-chamber pellet die apparatus;

FIG. 9 is an exploded bottom perspective view of the multi-chamber pellet die apparatus;

FIG. 10 is a right side view of the multi-chamber pellet die apparatus shown without the cover for clarity of illustration; and,

FIG. 11 is a top perspective view of FIG. 10.

The broken lines illustrating portions of the multi-chamber pellet die apparatus form no part of the claimed design.
